UNITED STATES PATENT OFFICE.

AVILA THOMAS, OF DETROIT, MICHIGAN, ASSIGNOR TO THOMAS STEEL REINFORCEMENT CO., OF DETROIT, MICHIGAN, A CORPORATION OF MICHIGAN.

EXPANSION-JOINT FOR CONCRETE ROADWAYS.

1,017,346.

Specification of Letters Patent. Patented Feb. 13, 1912.

Application filed October 25, 1911. Serial No. 656,558.

To all whom it may concern:

Be it known that I, AVILA THOMAS, a citizen of the United States, residing at Detroit, in the county of Wayne, State of Michigan, have invented certain new and useful Improvements in Expansion-Joints for Concrete Roadways; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to an expansion joint especially designed for use in the construction of concrete roadways but adaptable for other purposes, and consists in the combination, association, and arrangement of parts hereinafter more fully set forth and pointed out in the claims.

The object of the invention is to provide a simple and efficient expansion joint whereby any expansion and contraction in a roadway may be provided for so as to avoid cracking the concrete, the arrangement being such as to connect the members at the joint with the reinforcing members in the body of the concrete whereby the whole mass may be bound together for a given area and caused to move as a unit under varying conditions of temperature, provision being made for readily connecting the metal parts at the joint with the reinforcing bars in a manner to bind the parts firmly together and retain them securely in place.

The above object is attained by the structure illustrated in the accompanying drawings, in which:—

Figure 1 is a sectional view through a concrete roadway showing one embodiment of my expansion joint. Fig. 2 is a fragmentary view in elevation of one of the facing plates at the joint, showing one of the tension members in transverse section and the hooked end of said member in engagement with the integral tongue of said plate, which is curved to form an embracing eye for said hook. Fig. 3 is a plan view of the parts shown in Fig. 1, and in addition thereto showing one of the supporting standards carrying the longitudinal and transversely extending reinforcing bars or members.

Referring to the characters of reference, 1 designates the concrete of a roadway which

is reinforced by upper and lower longitudinal bars 2 and 3 respectively, and upper and lower transverse bars 4. These reinforcing bars are supported by suitable upright standards 5 preferably L-shaped in cross section, as shown in Fig. 3, and having laterally extending foot portions 6. There are a sufficient number of the reinforcing bars and of the supporting standards employed to form a frame-work of the crossed upper and lower bars sufficiently strong to tie together and unify the sections of the concrete mass, the reinforcing bars in said strengthening frame-work passing through and being supported in the wings of the L-shaped standards.

The concrete roadway is divided into sections or stretches of 30 feet more or less, and at the termination of each section there is employed a face plate 7 preferably of wrought metal, which is provided at intervals therein with tongues 8 struck or sheared therefrom so as to leave one end attached to the body of the plate. The free end of each tongue is formed into a partially closed eye 9 adapted to embrace the upwardly turned hook 10 at the end of each of the upper longitudinal bars 2. It will be noted that the sections of the concrete roadway, each consisting of a reinforced unified mass, are separated by an intervening space which is filled with an insertion of asphalt 11 or other compressible matter. At each joint the facing plates 7 are set into the edge of the concrete mass at the surface thereof so that the compressible filling 11 becomes interposed between them, as shown in Fig. 1. This filling oozes out of the space between the concrete sections when said sections expand, and recedes into and fills the space between said sections when they contract. The plates 7 at the surface prevent the edges of the concrete being broken off and at the same time serve to tie the whole mass together from end to end of each section by reason of the connection of the longitudinal tension members therewith through the engagement of the hook upon said tension members in the eyes of the tongues on said plates. This reinforcement prevents the cracking of the concrete mass at any point between the ends of the sections, and yet provides for expansion and contraction of the mass under extreme variations in temperature.

When the reinforcing frame-work is in position the facing plates 7 are set in place by passing the eyes in the tongues 8 thereof downwardly over the upwardly turned ends 5 of the hooks 10 of the tension bars 2. To spring said tongues outwardly so as to enable the hooked ends of said bars to readily enter said eyes, a pry or lever 12, as shown by dotted lines in Fig. 3, may be employed. 10 Upon removing said lever after the hooked end of the tension bar has been inserted in the eye of the hook the tendency of said tongue to spring back to its former position will firmly lock the hook in said eye and 15 hold the parts securely engaged under tension.

Having thus fully set forth my invention, what I claim as new and desire to secure by Letters Patent, is:—

- 20 1. An expansion joint for cementitious masses, comprising a reinforcing frame-work having tension members with hooked terminals, and opposed face plates set in the edges of the sections of the cementitious 25 masses at the surface thereof, said plates having members thereon engaged by the hooked terminals of the tension members to effect a connection between said parts. 2. An expansion joint for cementitious 30 masses, comprising a reinforcing frame-

work having tension members with hooked terminals, opposed face plates set in the edges of the sections of the cementitious masses and spaced to allow a filling therebetween, tongues on said plates having eyes 35 which receive the hooked terminals of the tension members, and a compressible filling between the cementitious masses and occupying the space between said plates.

3. A structure of the character described, 40 comprising tension members having hooked terminals, a face plate having tongues struck therefrom, the free ends of said tongues being formed into embracing eyes to receive the hooked terminals of the tension members to effect a connection between said members and said face plate.

4. An expansion joint for cementitious masses, comprising a reinforcing frame-work and opposed face plates set in the 50 edges of the sections of the cementitious masses, and means for connecting said face plates to said reinforcing frame-work in a manner to tie said parts together.

In testimony whereof, I sign this specification in the presence of two witnesses.

AVILA THOMAS.
